CARL H. BISSELL, OF SYRACUSE, NEW YORK, ASSIGNOR TO CROUSE-HINDS COMPANY, OF NEW YORK, N. Y., A CORPORATION OF NEW YORK.

INCANDESCENT-ELECTRIC-LAMP SOCKET.

1,250,129.

Specification of Letters Patent.

Patented Dec. 18, 1917.

Application filed June 22, 1911. Serial No. 634,769.

To all whom it may concern:

Be it known that I, CARL H. BISSELL, of Syracuse, in the county of Onondaga, in the State of New York, have invented a certain new and useful Incandescent-Electric-Lamp Socket, of which the following is a specification.

This invention has for its object the production of an incandescent electric lamp socket which is particularly simple in construction, economical in manufacture and highly efficient and durable in use; and it consists in the combinations and constructions hereinafter set forth and claimed.

In describing this invention reference is had to the accompanying drawings in which like characters designate corresponding parts in all the views.

Figure 1 is an elevation of my lamp socket, the casing therefor being shown in section.

Fig. 2 is another elevation thereof, the casing being removed.

Figs. 3 and 4 are, respectively, a vertical sectional view and an inverted plan of the lamp socket, the casing being removed, and one of the lamp contact terminals being also removed in Fig. 4.

Figs. 5 and 6 are, respectively, an elevation and a plan of the base of the socket additional parts being also shown.

Figs. 7 and 8 are, respectively, opposing face views of the sections of the base.

Fig. 9 is an elevation of the section shown in Fig. 8.

This incandescent electric lamp socket comprises, generally, a base having two sections, one of the sections being formed with a recess opening through the end face thereof opposed to the other section, and such other section serving as a closure for the recess, wire terminals and lamp contact terminals carried by the base, and a switch located in the recess.

1 and 2 are the sections of the base; 3 and 4 are the wire terminals carried by the base; and 5 and 6 are the lamp contact terminals. 7 is the casing of the lamp socket.

The section 1 of the base is formed with a recess 8 opening through its face opposed to the section 2, the recess being here shown

as also opening through diametrically opposite sides of the section 1 and as having one end enlarged as shown at 9, Figs. 5 and 7.

The section 2 serves as a closure for the recess 8 and the sections 1 and 2 are provided, respectively, with slots and projections entering the slots, the slots 10 being formed in the section 1 on opposite sides of the recess 8 and opening through opposite side walls of the recess, one of the slots opening through the side face of said section 1 and both of the slots opening through the end face of said section 1 opposed to the section 2; and the projections 11 are provided on the section 2 and fit into the slots 10.

The section 2 is also formed with a recess opposed to the recess 8 and having an inclined bottom 12, said recess opening entirely through the section 2 at one end forming a passage 13 for exposing the lamp contact terminal 5 to the switch in the recess 8. The lamp contact terminal 5 is the usual threaded shell or sleeve having a flange 14 which engages the base of the socket and is exposed to the switch through said passage.

The sections 1, 2 are held together by a pair of screws 15 extending lengthwise of the base and through the flange 14 of the sleeve terminal 5, openings 16 in the section 2 and openings 17 of the section 1, said screws 15 threading into nuts located in non-circular recesses 18 in the upper face of the section 1.

The wire terminal 3 is located in a lengthwise peripheral groove 19 extending lengthwise of the section 1 of the base and is formed with a lateral extension 20 lying in a groove in the inner end wall of the lateral extension 9 of the recess 8, and said terminal is held in position by a screw 21 extending lengthwise of the section 1 from the upper end thereof and threading into said extension 20.

The other wire terminal 4 is located in a peripheral groove 22, Fig. 2, extending lengthwise of the section 1, and is formed with one end looped as at 23, the end of the looped portion extending in a rigid angle 100 to the major part of the terminal and engaging the end wall of said groove in po-

sition to receive a screw 24 extending lengthwise of the section 1 from the upper end thereof, the screw 24 threading into the end of the looped portion 23 of the wire terminal. 5. The wire terminal 4 is formed with an integral extension which constitutes the central lamp terminal 6.

The grooves 19 and 20, slots 10 and all other passages and screw holes extend 10 lengthwise of the section 1, and open through the end face of the section 1 through which the recess 8 and its enlargement 9 open, so that the pattern for the section 1, which is usually insulating material cast into a mold, 15 can be easily drawn from the sand.

25, 26 are respectively the opposing arms of the switch located in the recess 8, the arms being fixed at corresponding ends and having their other ends movable respectively 20 into and out of contact with the wire terminal 3 and the flange 14 of the lamp contact terminal 5.

The arm 26 has its end portion 27 bent 25 backwardly into a position opposed to and spaced apart from the major part of such arm 26 so that said portion 27 moves through the passage 18 into and out of contact with the flange 14 of the sleeve terminal 5. Owing to said portion 27 the arm 26 is of maximum 30 length and resiliency.

The arm 25 is provided with an angular extension 28 at its ends, said extension extending toward the arm 25 and terminating in a contact piece movable into and out of 35 engagement with a portion of the wire terminal 3. Owing to the angular extension 28, the arm 26 is of maximum resiliency and the switch can be confined in a recess 18 of minimum depth.

40 The end portion 27 of the arm 26 and the end portion 28 of the arm 25 include parts arranged at substantially a right angle to the arms 25, 26 and parts extending in directions parallel to the major parts of said 45 arms; the parallel portion of the arm 25 extending in a direction opposite to that in which the parallel portion 27 of the arm 26 extends.

50 Preferably the arms 25 and 26 are bent from a single strip of metal, the intermediate portion of which is pressed together and engaged with walls of the recess, and the end of the pressed portion is bent at an angle forming an angular lug 29 for engaging 55 the bottom wall of the recess 8 and a wall meeting the bottom at an angle, Fig. 3. The lug receives a fastening screw 30 extending through the section 1 from the upper end thereof through the lug 29 and 60 into the nut 31.

32 is the shank of the key for the switch, the shank being mounted in bearings formed in the opposing faces of the sections 1, 2 and on opposite sides of the recess 8 so that upon

the detaching or the separation of the sections 1 and 2, the key can be easily removed. As here shown the bearings are alined grooves 33 formed in the end walls of the slots 10, and the shank 32 is held in the bearings by the projections 11. 65 70

34 is a cam mounted on the shank within the recess 8 between the arms 25, 26 and operating to separate the arms to cause them to make contact with the wire terminal 3 and the sleeve terminal 5 when the shank 75 is turned in one direction, and permitting said arms to break contact when the shank is turned in the opposite direction.

What I claim is:

1. An incandescent electric lamp socket 80 comprising a base, wire terminals and lamp contact terminals carried by the base, the base having two sections, one of the sections being formed with a recess opening through an end face thereof and the other section serving as a closure for the recess, the sections being formed respectively on their opposing faces with lengthwise slots and with projections for entering the slots, a switch located in the recess and including a key having a shank extending transversely through the slots at the inner ends thereof and being held in position by said projections, substantially as and for the purpose set forth. 85 90 95

2. An incandescent electric lamp socket comprising a base, wire terminals and lamp contact terminals carried by the base, the base having two sections, one of the sections being formed with a recess opening through an end face thereof and the other section serving as a closure for the recess, and the section formed with the recess being also provided with a slot opening inwardly from its face opposed to the other section, and terminating in a bearing at its inner end, a switch located in the recess and a key shank journaled in the bearing, the section serving as a closure having a projection for entering the slot and holding the shank in the bearing, substantially as and for the purpose described. 100 105 110

3. In an incandescent electric lamp socket, a lamp receiving shell, a base of insulation to which the base of the shell is attached, a wire terminal carried by the base of insulation, a switch member arranged within the base of insulation to make and break contact with the wire terminal and the lamp receiving shell, said member comprising a strip of resilient material bent to form substantially parallel arms extending transversely of the axis of the socket with their free ends normally out of contact with the wire terminal and the lamp receiving shell respectively, the intermediate part of the strip being pressed together and extending upwardly at an angle to said arms and being 115 120 125

secured to the top of the base of insulation, and a cam operating between the arms for pressing the same in contact with the wire terminal and the shell, substantially as and for the purpose set forth.

4. A switch member for an incandescent electric lamp socket comprising a strip of resilient material bent to form substantially parallel arms spaced apart, the intermediate part of the strip being pressed together to form a lug at one end of the member for receiving an attaching device, and the free end of one of said arms having a continuation extending toward the other arm and terminating in an angularly projecting part, substantially as and for the purpose specified.

5. A switch member for an incandescent electric lamp socket comprising a strip of resilient material bent to form substantially parallel arms spaced apart, the intermediate part of the strip being pressed together to form a lug at one end of the member for receiving an attaching device, the free ends of said arms having continuations extending in the same general direction and terminating in angularly disposed parts projecting in opposite directions, substantially as and for the purpose set forth.

6. A switch member formed of a single piece of resilient material and comprising main portions spaced apart for accommodating an operating cam, the free ends of said main portions having continuations extending perpendicular to the main portions and in parallelism therewith, and the opposite ends of said main portions having continuations extending substantially perpendicular thereto and in contact with each other, and terminating in portions disposed in parallel relation to the main portions and extending in the direction of the free ends thereof and providing an attaching lug, substantially as and for the purpose described.

7. In an incandescent electric lamp socket, a base of insulation having a recess, or chamber, extending transversely therethrough, and a passage leading from one end of the same through the front face of the base, a wire terminal member located at the rear of the chamber at the end thereof from which the passage leads, a sleeve terminal secured to the outer face of the base and having a part exposed through the passage, a switch member in the chamber having arms extending perpendicular to the axis of the base and having free ends coöperating, respectively, with the wire terminal and said part of the sleeve terminal, the opposite ends of said arms being arranged in juxtaposition, means for securing the same to the rear wall of the chamber adjacent the end thereof opposite to that first-named, and a key cam located in the chamber between the

arms for operating the same, substantially as and for the purpose specified.

8. In a lamp socket, a section of insulation having a recess therein opening through one end thereof, a switch cam operating in said recess, a switch carried by said section comprising two arms, one located between the cam and the bottom wall of the recess, and the other on the opposite side of the cam, a wire terminal carried by the section, a lamp terminal also carried by the section, a second section of insulation closing a part of said recess and having a passage way communicating with another part of the recess, and a lamp terminal shell mounted on said second section and having a part located in coöperative relation with said passage-way, substantially as and for the purpose set forth.

9. In a lamp socket, the combination with a base of insulation having a transverse recess with a part opening through its end, a key cam mounted in the recess substantially centrally between opposite ends thereof, a switch secured to the bottom of the recess adjacent one end of the same and including two resilient arms having substantially parallel portions extending toward the other end of the recess, and one located between the cam and the bottom wall of the recess, and the other on the opposite side of the cam, a wire terminal secured to the base adjacent said opposite end of the recess and in coöperative relation with the end portion of the first-named arm, and a lamp terminal shell supported on the base and having a part exposed adjacent the last-named end of the recess and in coöperative relation with the second arm of the switch, substantially as and for the purpose specified.

10. In an incandescent electric lamp socket, a base having a recess, or chamber, extending transversely therethrough, and a passageway leading from one end of the recess to the front face of the base, said base having at the opposite side and end of the recess surfaces disposed at right angles to each other, a wire terminal having a part arranged contiguous the rear wall of the recess at the first-named end thereof, a lamp terminal shell mounted on the face of the base and having a part exposed through the passage, a switch member having corresponding end portions in contact and of angular formation, said member of angular formation abutting against said surfaces disposed at right angles to each other, a screw for holding said part of angular formation against said surfaces disposed at right angles to each other, said switch member having parallel resilient arms spaced apart and extending in a direction perpendicular to the axis of the base, one of said arms having its free end portion bent toward the other

arm, and its extremity extending outwardly for coöperating with said wire terminal and the free end of the other arm being bent backwardly in a position to enter said passage and engage the portion of the shell terminal exposed therethrough, and an operating member having a part located in the recess between the two arms, and another part accessible exteriorly of the base, substantially as and for the purpose described.

In testimony whereof, I have hereunto signed my name in the presence of two attesting witnesses, at Syracuse, in the county of Onondaga, in the State of New York, this 19th day of June, 1911.
